UNITED STATES PATENT OFFICE.

AQUILLA H. GOSNELL, OF BALTIMORE, MARYLAND.

DESIGN FOR A BAKING-SHELL.

41,395.

Specification for Design.

Patented May 23, 1911.

Application filed March 21, 1911. Serial No. 616,033. Term of patent 14 years.

To all whom it may concern:

Be it known that I, AQUILLA H. GOSNELL, a citizen of the United States, residing at Baltimore, in the State of Maryland, have invented a new, original, and ornamental Design for Baking-Shells, of which the following is a specification, reference being had to the accompanying drawing, forming part thereof.

Figure 1 of the drawing is a plan view of a baking shell, showing my new design. Fig. 2 is a side elevation of Fig. 1.

I claim:

The ornamental design for a baking shell, as shown.

In testimony whereof I affix my signature in presence of two witnesses.

AQUILLA H. GOSNELL.

Witnesses:

CHAPIN A. FERGUSON,
WILMER EMORY.
